Inventor
WALTER J. BIRD.

By His Attorney

B. C. T. Rauber

UNITED STATES PATENT OFFICE.

WALTER JUDSON BIRD, OF FLUSHING, NEW YORK.

MENU HOLDER.

Application filed October 21, 1925. Serial No. 63,852.

My present invention relates to a menu holder or device of similar type and more specifically to a holder of book like form adapted to carry advertisements and to support a menu card or folder between its covers.

Menu holders have heretofore been constructed of cover members having metal frames supporting a sheet or card of paper carrying advertisements, enclosed between transparent sheets, and hinge members joining the cover members and having interengaging parts. This construction, however, provided a number of crevices in which dust and moisture collected, creating an unsightly and unsanitary condition and tending to cause rusting and deterioration of the holder. This condition also frequently resulted in a discoloring of the advertisements and thus impaired their attractiveness and value.

An object of my present invention is to provide a menu holder or device of similar type in which the use of interfitting hinge elements or other elements forming crevices is avoided and a minimum of joints is afforded and which has a smooth, book-like appearance.

Another object of the invention is to provide a menu holder or device of similar type in which the cover plates are of solid, polished, celluloid, or similar material, secured to hinge elements without the necessity for an enclosing, supporting border or frame.

A further object of the invention is to provide a simple and effective menu securing means.

A still further object of my invention is to provide a device of the above indicated type of which the cover members may be readily removed and remounted for cleaning or replacement.

With these and other objects in view, which may be perceived from the following description, the invention comprises the device described and set forth in the following specification and claims.

The various features of the invention are illustrated in the accompanying drawings, in which:

Fig. 1 is a perspective view showing a menu card holder embodying a preferred form of my invention and illustrating the manner of using the holder,

Fig. 2 is a perspective view of the menu holder, parts being shown as broken away to more clearly illustrate its construction,

Fig. 3 is a longitudinal vertical section through the back element of the holder,

Fig. 4 is a front view of the holder in open position, portions of the cover plates being broken away to save space in the drawing, and the holder being shown on a reduced scale for the same purpose,

Fig. 5 is a sectional view of a portion of the holder taken on line 5—5 of Fig. 4, and,

Fig. 6 is a front view of a holder having a modified and improved mounting for the pintle elements on which the cover plates are mounted.

In my present invention, the menu holder is formed of a pair of cover plates 10 and 11 supported on a pair of spaced pintles 12 and 13, mounted at their ends in lugs 14 and 15 projecting forwardly from the ends of a back or supporting strip 16. The back strip 16, not only serves to support and hold the pintles 12 and 13 and the cover plates 10 and 11 in position, but also closes the space back of the cover plates and gives the holder a smooth book-like appearance, being preferably rounded convexly as shown in Fig. 5, to increase the book-like appearance as well as to give greater strength and rigidity.

The cover plates 10 and 11 may be of any suitable construction, but are preferably each constructed of a single, integral sheet or board of celluloid or similar material, preferably of the kind not readily ignited, on which the advertisements are printed directly. The plates are made of sheets of sufficient thickness and strength to form cover plates without reinforcing frames or borders.

The cover plates 10 and 11 are pivotally mounted on the pintles by means of strips of sheet metal 17, which are bent at 18 about the pintles to form a pair of forwardly projecting parallel wings 19 and 20 between which the rear edge portions of the celluloid sheets 10 and 11 extend and to which these sheets are secured by means of rivets 21 extending through the strips and celluloid plates. The plates 10 and 11 may be removed from the strips 17 by drilling out or cutting away the rivets 21 and new plates may thereupon be inserted between the

wings 19 and 20 and secured in place. The strips 17, when assembled with the plates 10 or 11 serve as hinge leaves, swinging about the pintles 12 and 13.

5 In the preferred manner of mounting the pintles, illustrated in Fig. 6, one end of the pinte is threaded as at 22 and is received in an opening or socket in the supporting lug 14, the other end of the pinte as at 23 being supported in a smooth opening 24 in the opposite lug 15 through which it may slide when the threaded end of the pinte is unscrewed. The end 23 is provided with a groove 25 for the reception of a screw driver 10 to unscrew and remove the pinte. Upon unscrewing the end 22, the other end 23 will project slightly from the opening 24 and permit the pinte to be drawn out, releasing the hinge leaves 17 and covers 15 20 and 11.

To provide additional support for the pintles 12 and 13, one or more intermediate lugs 26 may be mounted on the forward or inner surface of the back strip 16 and provided with openings through which the pintles may extend and be supported. The strips or leaves 17 are suitably notched as at 25 27 to receive the lug or lugs 26.

The back strip 16 also serves to support a menu card or folder 28 between the cover plates 10 and 11. Any suitable means may be used to secure the card or folder to the back strip. In the preferred form of holding or securing means, however, a wire or pin of spring metal or resilient material is provided with an S shaped end 29 the end lap 30 of which is soldered or otherwise secured to the front or inner face of the strip 16. The pin is off-set at 31, adjacent 30 the S shaped portion, towards the strip 16 and then extends lengthwise of the forward or inner face of the strip. The pin is given a bend that causes its free end 32 to project forwardly at an angle to the strip 16 to enable the card 28 to be threaded thereon. The free projecting portion 32 is retained and locked in a position slightly spaced from the strip 16 by means of a forwardly projecting hook 33.

50 In mounting the folder or card 28 on the pin, the free portion 32 of the pin is inserted through a hole 34 in the menu card, which is then slipped lengthwise of the pin and over the S shaped portion until it lies 55 against the S lap 30. A second, suitably spaced opening 35 in the menu card is then fitted over the hook 33 and the free, projecting end 32 of the pin is hooked under the hook, thereby holding the card in position.

60 It is to be understood that holes 34 and 35 are formed in the crease or fold of the menu card or folder to form symmetrical pages. The S portion of the pin projects beyond the opening 34 as at 36 and the portion 32 of the 65 pin similarly projects beyond the opening 35

so that the folder is supported on both sides of the holes 34 and 35 and there is therefore less tendency for the folder to tear away.

It is desirable to have the plates 10 and 11 resiliently held in a partly opened position 70 so that when set on end and released, they will take the position shown in Fig. 1 and remain upright, while they may easily be closed tightly or opened to a flat position. For this purpose, a coiled, or other suitable 75 form of spring 37 is provided and held in position by being looped around the pintles 12 and 13 and then projects between the wings 19 and 20 of the hinge leaves 17, the plates 10 and 11 being notched as indicated 80 at 38 in Fig. 4 to receive the ends of the spring. The spring 37 is given the form required to hold the covers 10 and 11 in the required position but the spring is weak enough to permit the cover plates 10 and 11 85 to lie flat when the holder is opened.

As changes of construction could be made within the scope of my invention, it is desired that all matter contained in the above description or shown in the accompanying 90 drawings shall be interpreted as illustrative and not in a limiting sense.

Having described my invention, what I claim and desire to secure by Letters Patent is:

95

1. A device of the type described which comprises, a back strip having forwardly projecting end lugs, a pair of spaced pintles extending lengthwise of, and slightly spaced from the side edges of said back strip and mounted at their ends in said end lugs, a pair of plates hinged on said pintles, means for resiliently holding said plates in partly opened position, and means for securing a menu card to said back strip between said plates.

2. A device of the type described which comprises, a back strip having forwardly projecting end lugs, a pair of spaced pintles extending lengthwise of, and slightly spaced from the side edges of said back strip, one end of each pinte being threaded in one of said end lugs and the other end extending into an opening in the other lug, a pair of plates hinged one on each of said pintles, means for resiliently holding said plates in partly opened position, and means for securing a menu card to said back strip between said plates.

3. A device of the type described which comprises, a supporting back strip, a pair of spaced pintles extending lengthwise of the said edges of said back strip and mounted at their ends on said back strip, a pair of cover plates, one hinged on each of said pintles, means for resiliently holding said plates in partly opened position, and means for securing a menu card between said cover plates.

4. A device of the type described which 130

comprises, a back strip, a pair of spaced pintles mounted at their ends on, and extending lengthwise of and slightly spaced from the edges of, said back strip, a pair of 5 hinge leaves, one for each pintle, said hinge leaves comprising a strip of metal bent about their respective pintles and extending in a pair of spaced wings, a pair of solid, printed, cover plates of stiff celluloid material, one edge of each plate being inserted 10 between and secured to said spaced wings, and means for resiliency holding said cover plates in partly opened position.

5. A device of the type described which 15 comprises, a back strip, a pair of cover plates hinged to said back strip, and means for securing a card or folder to said back strip between said cover plates comprising a pin

having an S-shaped end secured to the inner face of said back strip and extending therefrom in a slightly spaced lengthwise position, and a hook on said back strip to hold the free end of said pin.

6. A device of the type described which comprises, a pair of plates, a hinge element 25 connecting said plates, and a means for securing a menu card between said plates comprising a pin having an S-shaped end secured to said hinge element and a projecting portion extending lengthwise of and 30 spaced from said hinge element, and a hook on said hinge element for retaining said free end of said pin.

In testimony whereof I affix my signature.

WALTER JUDSON BIRD.
